UNITED STATES PATENT OFFICE.

CLARENCE W. COLE, OF LOS ANGELES, CALIFORNIA.

REFLECTOR.

1,259,364.

Specification of Letters Patent. Patented Mar. 12, 1918.

Application filed July 7, 1917. Serial No. 179,168.

To all whom it may concern:

Be it known that I, CLARENCE W. COLE, a citizen of the United States, residing at Los Angeles, in the county of Los Angeles 5 and State of California, have invented new and useful Improvements in Reflectors, of which the following is a specification.

This invention relates to reflectors, and especially to that type of hood reflectors 10 used for concealed lighting of show cases.

It is an object of the invention to provide a hood reflector which can be quickly and securely attached to and detached from a display case without the use of special tools or 15 mutilation of the case.

Another object is to provide in a hood reflector detachable means for supporting the lamps and carrying the electrical wires so that the lamps may be conveniently renewed 20 without special socket mechanism.

Heretofore, reflectors have been constructed having a reflecting hood in which the lamp socket is secured by special socket means, so that the socket may be detached or swung 25 outwardly into a position for removing and inserting lamps. A channel for electric wires has been fixedly secured to the hood. In addition to these features of construction, securing members have been provided 30 for attachment of the hood to the case. Such devices are objectionable by reason of their complex and cumbersome structure, and the inconvenience experienced in renewing the lamps.

35 I obviate these objections by providing a hood reflector within which is disposed a channel member serving the double purpose of carrying the wires and supporting the lamps. Supporting straps of ductile material are secured to the channel member and pass through apertures in the hood, thereby 40 providing a support for the entire reflector, all parts being concealed in the hood and removable therefrom for repair and renewal 45 of lamps.

I accomplish these objects by the embodiment of my invention shown in the accompanying drawing, in which:

Figure 1 is an elevation of my improved 50 reflector installed in the corner of a show case.

Fig. 2 is a vertical section taken on the line 2-2 of Fig. 1.

Fig. 3 is a view showing the channel re- 55 moved from the reflector and having an electric socket mounted thereon.

Fig. 4 is a perspective view of one of the supporting straps.

More specifically, 5 indicates the horizontal wall of a show case and 6 a vertical 60 wall, the structure shown being of the type in which glass forms the walls which are cemented to each other as indicated at 7. Mounted within the corner formed by the intersection of walls 5 and 6 is my improved 65 hood reflector, comprising a reflector body formed preferably of metal with a reflecting coating on the inside, such as white enamel. The reflector hood is elongated and has two walls 8 and 9 intersecting at right angles to 70 form a structure which will fit closely in the corner of the case. The angle, may, however, be made of any other degree suitable for show case walls which do not have corners forming angles of 90 degrees. A downwardly sloping wall 10 is provided to direct 75 the light upon the articles displayed and to conceal it from the observer.

Within the hood is mounted a channel member 14 comprised preferably of a strap 80 bent to have a substantially triangular cross section, thereby providing a channel within which the electric wires may be placed. The channel member has its face 15 formed with a coating which will reflect the light and an 85 aperture therein in which is secured an outlet post 16 adapted to carry an electric lamp socket 17. Electric wires 18 pass into an outlet 20 secured to one of the end walls of the reflector through the channel member 90 14 and post 16, and are secured to a lamp socket 17 in the usual manner. One end of the channel member is provided with a bent up tongue 21 to accommodate the inner end 95 of outlet 20 within the reflector and to completely conceal the same, and at the same time present a uniform reflecting surface.

It will be noted that the channel member is formed so that the walls 22 and 23 do not intersect, but leave slots through which are 100 passed straps 24 and 25; these straps are of form shown in Fig. 4 having an end 26 bent at right angles to the body and pass through slots 27 formed in the base of the channel member 15, the bent end 26 engaging 105 the channel member 14 and holding it securely in place within the reflector.

To mount my improved hood reflector in the show case, the electric wires are passed through an outlet 20 in one of the end walls 110 of the hood and connected to the socket 17 of the lamp 28. Lamp 28 is secured in socket

17 and then the straps 24 and 25 are passed through slots formed in the corner of the hood, the channel member being positioned closely against the corner, through the channel member and slots 27, the ends being bent at right angles against the outer face of the channel member, thus securely holding the channel in place in the reflector. The cement between walls 5 and 6 is dug out with 10 a knife at the point where the hood is to be supported by the straps, and straps 24 and 25 are passed through the apertures thus formed and bent downward at the ends as indicated at 29, thus securing the reflector 15 in place.

The reflector may be formed of any desired length and several lamps mounted on the channel member and connected to the electric wires in parallel.

20. The lamps may be easily and readily renewed when occasion requires, and it will be at once apparent that by providing a removable channel member carrying the lighting fixtures that the reflector may be easily 25 mounted in a show case with little or no trouble, and further without injury to the cases to which they are secured.

What I claim is:

1. The combination with a display case, 30 of a corner hood lamp reflector mounted therein, said reflector comprising a body member adapted to fit a corner of said display case, a substantially triangular and removable lamp supporting member mounted

in the corner of said hood, and supporting 35 straps secured to said member and passing through said hood to secure said hood and lamp supporting member in position in said case.

2. The combination of a display case, of a 40 corner hood lamp reflector mounted therein, said reflector comprising a rectangular body member adapted to closely fit in a corner of said display case, said hood having slots in 45 its corner, a substantially triangular removable lamp supporting member mounted in said hood, and flexible straps secured to said lamp supporting member and passing through the slots in said hood and through said display case to detachably secure said 50 hood and lamp supporting member in said display case.

3. A corner hood reflector for display cases, comprising a hood having walls disposed to closely fit into the corner of a display case, a channel member provided with walls and adapted to closely fit into the corner of the hood, said member having an outlet for the passage of electric conductors, flexible straps detachably secured to said 60 channel member and passing through slots in the hood at the corners thereof and adapted to secure said hood to the display case.

In witness that I claim the foregoing I have hereunto subscribed my name this 21st 65 day of June, 1917.

CLARENCE W. COLE.
